UNITED STATES PATENT OFFICE.

CHARLES T. BROWN, OF CHICAGO, ILLINOIS, ASSIGNOR TO FLORA L. BROWN,
OF SAME PLACE.

LOCK-HOOK.

SPECIFICATION forming part of Letters Patent No. 404,161, dated May 28, 1889.

Application filed February 8, 1888. Renewed March 18, 1889. Serial No. 303,823. (Model.)

To all whom it may concern:

Be it known that I, CHARLES T. BROWN, a citizen of the United States, residing at Chicago, in the county of Cook and State of Illinois, have invented certain new and useful Improvements in Hook-Catches, of which the following is a specification.

The invention relates to an automatic locking device adapted to catch and retain a hook upon the stud or post which it detachably engages, the catch and hook together constituting what may be termed an "automatic lock-hook."

The locking device consists of two disks rotatively mounted on a post or stud, each disk having a lug or ear thereon, the one ear yieldingly held opposite the other by a spring which is placed between the disks. In closing the hook upon the stud one ear is carried forward by engagement with the heel of the hook, and the other ear is carried by the spring to a position back of the hook as soon as the latter is closed upon the stud, thus locking the hook against accidental detachment.

In the construction illustrated in the accompanying drawings, showing a practicable form of my invention, this spring is retained in annular grooves in the disks.

The hook entering into the device performs the same work in the same way as an ordinary hook; but it is slightly changed in form on that part thereof which may be termed the "heel," and which, in the engaging of the hook upon its stud, actuates the locking device.

Figure 1 is a plan view of the hook and of the locking device forming the catch which retains the hook upon its stud. Fig. 2 is a cross-section of the hook and of the locking device on line 2 2 of Fig. 1. Fig. 3 is a plan view of the lower plate or disk forming a part of the locking device and of the base to which the hook is pivoted. Fig. 4 is a plan view of the under side of the upper disk forming a part of the locking device and of the under side of the pivoted end of the hook.

Like parts are designated by like letters of reference throughout the several views.

X is the base on which are mounted the disks constituting the locking device for the hook.

X' is the base to which the hook is pivoted. A is the hook, and a is the post on which it is pivoted.

a' is the curved end of the hook. a'' is the heel, and a''' is the bottom of the notch of the hook.

B is the lower disk of the locking device, having a central opening by which it is rotatively mounted on the post C.

B' is the upper disk of the locking device, having a central opening by which it also is mounted on the post C. The post C is rigidly secured in the base X, and has a head which retains the disks thereon. This post C forms the stud which the hook engages.

b is the lug or ear on the disk B, and b' is the lug or ear on the disk B'.

b'' is a hub on the disk B', extending upward to the head of the post C. This hub b'' is not, however, a necessary feature in the disk, as the post C from the head thereof to the upper face of the disk may be of about the diameter of the hub b'', and the shoulder thereby formed on the post will serve to maintain the disks in proper position.

D is the spring placed between the two disks in the annular coincident grooves E E'. In the annular groove E there is placed the stop e, having, as shown, an opening or way through it, and in the groove E' there is a stop e', adapted to pass through the opening in stop e when the disks are mounted in place on the post C. When the stop e' is in the opening in stop e, the ears b b' are opposite each other, and the spring D will then press against each side of stops e e'.

In engaging the hook with its stud or post C the heel a'' of the hook comes in contact with one or the other of the ears b b'. In Fig. 1 the hook is illustrated in full lines, with the heel thereof in contact with the ear b. By forcing the hook down upon its stud the ear b and the disk B, of which the ear is an integral part, rotates in the direction indicated by the arrow thereon and into the position indicated by the dotted ear b''' between the point and the heel of the hook. The ear b' is prevented from rotating in unison with the ear b by the rounded end a' of the hook until the bottom of the notch a''' is nearly or quite in contact

with the stud, and when the hook is thus in engagement with the stud the spring D, compressed by the turning of the disk B, turns the disk B' into a position back of the hook-bow, as illustrated by the dotted ear lettered b''''. The ear b''', standing between the point a' of the hook and the heel a'' thereof, is held firmly in its position by such point and heel, and the opposite ear is yieldingly held by the force of the spring D in position back of the bow of the hook, where it forms a lock, holding the hook on its stud.

The hook A may be mounted on a pivot in the ordinary way; but in the smaller sizes of the structure embodying the invention I prefer to mount it upon the pivot a, and to provide a spring, D', engaging with the hook and with the base or pivot, so that when the hook is not locked upon its stud the spring D' will 20 retract it and hold it retracted.

In Figs. 2 and 3 of the drawings an annular groove, x'', in the base x', suitable for inclosing a spring, is illustrated with a stop, x''', therein. The spring D' is placed in the groove x''. When the stop A' is against stop x''', the hook A is at right angles to the position it occupies when engaged with its stud C, and the tendency of the spring D' is to retain it in this position. When the hook is 30 brought forward and engaged on its stud, the spring is compressed, and has a tendency to retract the hook from the stud, whereon it is held by the locking device.

To release the hook from engagement with the stud the disk B' is turned around by the hand until the ear b' thereon is at the side of the curved end a' of the hook and in its original position, whereupon the hook will be retracted by the spring D'. The retraction of 40 the hook may be aided by the tendency of disk B to rotate into position with the ear b opposite the ear b'.

In the device when constructed as described the disks turn freely on post C when the hook is not engaged with such post, and hence either ear may be rotated by the heel a'' of the hook coming in contact therewith as the hook is pressed into engagement with the stud. When the heel of the hook rotates 50 b' and disk B', the stop e' passes out from the opening or way in stop e at the other side from which it passes out of such opening when the ear b is rotated by the hook, as last described, and compresses the spring D from 55 the other end thereof.

If the stop e' be placed out of line with the opening in stop e, it of course cannot pass through such slot, and in such case the heel a'' of the hook will necessarily actuate one 60 only of the ears b b'. I prefer, when the stop e' is so placed, that the ear b on the under disk, B, shall be that one which will pass around the head of the hook to the back

thereof, and the ear b' will then be the one actuated by the heel a'' of the hook. The 65 stop X''' is then provided on the base X to prevent complete rotation of the locking-disks.

I also prefer at times to place the disks B B' with the ears b b' directed toward the 70 base, so that the ears shall be between the disks and the base. The hook A in that case engages its stud between the locking-disks and the base X. The construction of the two disks so placed may be identical with that 75 hereinbefore described. When the locking-disks are thus placed on the post C, it will be preferable to place the retracting-spring D' (if employed) outside, and to put a stationary cap over the pivoted end of the hook, said 80 cap having therein the groove x'' to receive the spring. In either of the two ways described of placing the locking-disks upon the post or stud C, when the stop e' is located out of line with the opening in stop e, a spiral 85 spring having coils of larger diameter than the one illustrated in Fig. 2 and of the same diameter as the ring formed by the annular grooves E E' around the post a, may be used, being so placed in the grooves that one end 90 thereof is engaged with stop e and the other end with stop e'.

I do not wish to be restricted to the particular details above set forth, inasmuch as various changes can obviously be made without departing from the principle of the invention; but as a special construction the arrangement of the disks with their ears directed inwardly toward the base forms the subject of another application for Letters 100 Patent, Serial No. 303,651, filed of even date herewith.

Having thus described my invention, what I claim, and desire to secure by Letters Patent, 105 is—

1. A locking device for a hook, consisting of a post, two disks rotatively mounted on the post, an ear on each of the disks extending into the plane of the hook, and a spring engaging the disks and yieldingly holding the ears substantially opposite each other, substantially as described.

2. A locking device for a hook, consisting of a post, two disks rotatively mounted on the post, an ear on each of the disks extending into the plane of the hook, and a spring engaging the disks and yieldingly holding the ears substantially opposite each other, in combination with a pivoted hook and a spring arranged to retract the hook from the post 115 when released from the locking device, substantially as described.
